US0D1092329S

(12) **United States Design Patent** (10) Patent No.: **US D1,092,329 S**
(45) Date of Patent: ** Sep. 9, 2025

(54) **SHIFT PLATE ADAPTOR FOR A VEHICLE TRANSMISSION SHIFT ASSEMBLY**

(71) Applicant: **DARK MATTERX LLC**, Springfield, OR (US)

(72) Inventor: **Erik Daniel Grassauer**, Springfield, OR (US)

(73) Assignee: **DARK MATTERX LLC**, Springfield, OR (US)

(**) Term: **15 Years**

(21) Appl. No.: **29/936,859**

(22) Filed: **Apr. 10, 2024**

(51) **LOC (15) Cl.** **12-16**

(52) **U.S. Cl.**

USPC **D12/179**

(57) **CLAIM**

The ornamental design for a shift plate adaptor for a vehicle transmission shift assembly as shown and described.

DESCRIPTION

FIG. 1 is a perspective view of a shift plate adaptor for a vehicle transmission shift assembly showing our new claimed design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines depict environmental structure that forms no part of the claimed design.
